FRANCISKA BERG, OF NEW YORK, N. Y.

PORTABLE FOLDING DESK.

1,198,180.

Specification of Letters Patent. Patented Sept. 12, 1916.

Application filed September 8, 1915. Serial No. 49,421.

To all whom it may concern:

Be it known that I, FRANCISKA BERG, a subject of the King of Norway, and a resident of the borough of Manhattan, city, 5 county, and State of New York, have invented certain new and useful Improvements in Portable Folding Desks, of which the following is a specification.

The object of my invention is to provide 10 a simple, cheap but effective foldable and portable desk for convenient personal use,— a device that may be collapsed into flat, compact form for storage or transportation, and as readily extended and adapted to the 15 various requirements of use as a support for reading matter, writing materials, &c., as hereinafter more fully set forth,—the invention consisting in the specific construction and arrangement described and claimed.

20 In the accompanying drawings, Figure 1, is a view of the interior of my device as opened up and laid flat for convenience in showing the structure, although the device may or may not be used in such extended position; Fig. 2, shows the device as adjusted for use as a reading desk; Fig. 3, represents an end view of the device as ordinarily folded for use on the flat, or for storage or transportation.

30 Basically the device consists of rigid twin boards or leaves B, B', permanently united on their inner sides by flexible ligaments b^x, b^x, which, when the device is set up as a reading desk, as in Fig. 2, act to limit the 35 convergent spread or straddle of the desk boards B, B', as related to each other when the adjacent longitudinal edges b, b', are articulately connected by the coupling straps b², b², permanently attached to one board 40 and detachably connected with the other board, as by "glove button" fastenings f, f, or any other equivalent detachable fastening devices. In other words the flexible ligaments b^x, b^x, perform the double function 45 of permanently uniting the desk boards B, B', and of acting as stays to prevent the collapse outward of the device when adjusted as in Fig. 2, for use as a reading desk,— it being understood that normally the inner 50 edges b, b', of the desk boards B, B', are hinged together, as it were, by the coupling straps b², b², although the latter admit of ready detachment from one board so that both boards may be spread out flat in a common plane as shown in Fig. 1, if desired for any reason, as to give free access to the

pocket or portfolio P, or to afford an extended flat supporting surface, or for packing or storing in extended position if desirable, or for any other reason. 60

The back of the portfolio P, may be permanently attached to the inner side of either one or the other of the desk boards B, B', and may be made with one or more compartments for the accommodation of writing paper, memoranda, or other flat articles or material which it is desired to keep conveniently accessible for use in connection with the desk. The flap p, may be held closed by a cord fastening p', of well known 70 character as shown in Fig. 1, or by any other suitable fastening or expedient.

The outer or lower edges of the desk boards B, B', are formed with concavities b³, b³, terminating at each end of the device 75 in feet b⁴, b⁴, the latter adapted to rest on a flat surface as illustrated in Fig. 2, while the concavities b³, b³, are better adapted to rest on a curved surface or surfaces, as upon the body of a person recumbent, or reclining, or on the knees of a person seated, &c., according to the exigencies of use.

S, is a shelf articulately connected at its inner edge with the front side of one of the desk boards, as B, in the drawings, and 85 adapted to fold up against the same, as indicated in Fig. 3. When extended substantially at right angles thereto as shown in Fig. 2, it may be used as a support for a book, pamphlet or the like, being sustained 90 in such serviceable position by the flexible bracket-loops s, s, the ends of which are firmly secured to the desk board. These bracket-loops s, s, are each of the same length, just sufficient to support the shelf S, 95 in extended position substantially at right angles to the face of the desk board to which it and they are attached as shown in Fig. 2, and hence they, the bracket-loops s, s, afford ample scope for the folding over of the shelf 100 S, against the face of the desk board as shown in Fig. 3,—by reference to which it will be seen that when the shelf S, is thus folded back the bracket loops are slack, they being taut only when held so by the shelf S, 105 in its extended or operative position.

A retaining cord R, is positioned above the shelf S, being permanently attached at one extremity to one end of the desk board; and a temporary fastening device r, being 110 provided at the other end of the desk board by which the free end of the retaining cord

R, may be detachably secured after being passed across a book or the like, to hold the leaves or surface open or extended, as well as to retain the article in position on the shelf S, and against the inclined face of the desk board upon which the shelf S, is mounted.

While I do not limit myself in this respect, I prefer to make the desk boards B, 10 B', and shelf S, of stiff, light weight cardboard or the like, to facilitate transportation, manipulation, &c., as well as to economize in initial expense. There is another advantage in making the device cheap and 15 mainly of cardboard or other combustible material, in that it is then adapted to be readily burnt as a precautionary measure of sanitation after use by a person or persons afflicted with contagious disease. In fact it 20 is especially adapted to the requirements and convenience of sick persons and convalescents, and to the use of old or feeble persons, as well as for general use, either as a reading or writing desk, or as a medium of 25 support for other articles or material.

It is to be noted that when the desk-boards are opened up as in Fig. 2, for use as a book support or the like, the weight of the desk or article or articles placed thereon 30 will be shared by the desk boards in such manner that if the device rests upon the person of the user, the latter will not be hurt or inconvenienced thereby,—and this result is further assured by the concavities b³, b³, 35 formed in the lower portions of the boards B, B', which are thus made to conform in a

general way to the person of the user, thereby distributing the weight and strain over a relatively large contact surface and preventing the feet b⁴, b⁴, from causing uneven and 40 uncomfortable pressure.

What I claim as my invention and desire to secure by Letters Patent is,

1. The portable folding desk described comprising rigid twin leaves, flexible ligaments permanently uniting the same on their inner edges and limiting the convergent spread of said leaves and preventing the collapse thereof, and means permanently connected to the longitudinal edge of one 45 leaf and detachably connected with the adjacent longitudinal edge of the other leaf to articulately connect said leaves.

2. The portable folding desk described comprising rigid twin leaves, flexible ligaments permanently uniting the same on their inner edges and limiting the convergent spread of said leaves and preventing the collapse thereof, means permanently connected to the longitudinal edge of one leaf and 50 detachably connected with the adjacent longitudinal edge of the other leaf to articulately connect said leaves, and flexible bracket loops connected to the leaf near its outer edge and adapted to support a shelf and 55 adapted to be held taut when the shelf is in its operative position.

FRANCISKA BERG.
